US00D605236S

(12) **United States Design Patent**
Sinisi et al.

(10) **Patent No.:** **US D605,236 S**
(45) **Date of Patent:** **** Dec. 1, 2009**

(54) **INTERLOCKING TOY**

(75) Inventors: **John Jay Sinisi**, Warminster, PA (US); **Emily Matt**, Warminster, PA (US); **Joel Carpenter**, Warminster, PA (US); **Jon Hughes**, Warminster, PA (US); **Aaron Weinstock**, San Rafael, CA (US)

(73) Assignee: **ZinkoTek**, San Rafael, CA (US)

(**) Term: **14 Years**

(21) Appl. No.: **29/313,696**

(22) Filed: **Feb. 3, 2009**

Related U.S. Application Data

(62) Division of application No. 29/308,348, filed on Jun. 11, 2008, now Pat. No. Des. 588,208.

(51) **LOC (9) Cl.** **21-01**

(52) **U.S. Cl.** **D21/502**

(58) **Field of Classification Search** D21/390, D21/484, 485, 486, 488, 489, 491, 492, 494, D21/500, 501, 502, 503, 504, 632; D25/113, D25/114, 115, 116, 117; 446/69, 85, 101-128; 434/208, 259, 403; 273/153, 156, 160; 52/578; D8/382
